UNITED STATES PATENT OFFICE.

WILLIAM SIGESKE, OF PHILADELPHIA, PENNSYLVANIA.

DESIGN FOR A GAS BURNER.

60,271.

Specification for Design.

Patented Jan. 17, 1922.

Application filed February 23, 1921. Serial No. 447,324. Term of patent 3½ years.

To all whom it may concern:

Be it known that I, WILLIAM SIGESKE, a citizen of the United States, residing at Philadelphia, in the county of Philadelphia and State of Pennsylvania, have invented a new, original, and ornamental Design for Gas Burners, of which the following is a specification, reference being had to the accompanying drawings, forming part thereof.

The figure is a perspective view of a coal gas burner, showing my new design.

I claim:

The ornamental design for a gas burner, as shown.

WILLIAM SIGESKE.
